UNITED STATES PATENT OFFICE

151,648

DESIGN FOR A HOUSE

George M. Marrow, Brattleboro, Vt.

Application September 26, 1947, Serial No. 141,596

Term of patent 14 years

(Cl. D13—1)

To all whom it may concern:

Be it known that I, George M. Marrow, a citizen of the United States of America, residing at Brattleboro, in the county of Windham and State of Vermont, have invented a new, original, and ornamental Design for a House, of which the following is a specification, reference being had to the accompanying drawings, forming a part thereof, wherein:

Fig. 1 is a front elevation of a house illustrating my new design;

Fig. 2, a rear elevation; and

Fig. 3, a top plan view.

I claim:

The ornamental design for a house, as shown.

GEORGE M. MARROW.
